FIREARM RECEIVER

Frank F. Burton, Mount Carmel, and William C. Roemer, New Haven, Conn., assignors to Winchester Repeating Arms Company, New Haven, Conn., a corporation of Maryland

Application June 17, 1932, Serial No. 617,766

2 Claims. (Cl. 42—1)

This invention relates to an improvement in firearms such, for instance, as rifles, shotguns, etc., and relates in particular to an improvement in the so-called "receiver" portion or member 5 thereof.

One of the objects of our present invention is to provide a neat, attractive and workmanlike firearm receiver.

A further object of our present invention is 10 to provide a receiver of such character as may be produced at a relatively low cost for manufacture.

A further object of our invention is to provide a strong and rugged firearm receiver of such 15 character as will permit the convenient installation of the moving parts thereto.

Other objects will, from the following and the accompanying drawing, be apparent to those skilled in the art.

20 In the accompanying drawing:

Fig. 1 is a view in side elevation of one form which a receiver embodying our invention may assume;

Fig. 2 is a transverse sectional view thereof, 25 taken on the line 2—2 of Fig. 1, but on a larger scale;

Fig. 3 is a corresponding view taken on the line 3—3 of Fig. 1;

Fig. 4 is a broken detail sectional view taken 30 on the line 4—4 of Fig. 1, but on a larger scale;

Fig. 5 is a similar view taken on the line 5—5 of Fig. 1;

Fig. 6 is a view of the receiver body looking toward the open side face thereof;

35 Fig. 7 is a face view of the closure plate; and

Fig. 8 is a view looking toward the top edge of the closure plate.

In the embodiment of our invention herein chosen for illustration, we employ a receiver body 40 preferably produced by a forging operation and generally designated by the numeral 10. As shown, the said body is provided with a top wall 11, complementary bottom wall 12, rear wall 13 and a complementary front wall 14. The said 45 walls 11, 12, 13 and 14 are formed integral with a flat side wall 15 and laterally offsetting therefrom to produce a hollow body-member open on one face and having a cavity 16 therein for the reception of such moving parts, etc., as it may 50 be desired to install therein.

Mounted in the front wall 14 of the receiver body 10 and forwardly projecting therefrom is a gun-barrel 17 and a magazine-tube 18 extending in substantial parallelism in accordance 55 with the usual practice. The rear wall 13 of

the said receiver body is formed with a threaded bore 19 receiving the externally-threaded stem 20 formed at the forward end of a stud-like receiver-shank 21 which extends rearwardly from the said body-member in a slightly down- 60 wardly-inclined direction and is formed in its rear end with an internally threaded bore 22 receiving the threaded forward end of a butt- stock-retaining screw 23.

The rear face of the rear wall 13 of the receiver body 10 is formed with a groove 24 receiving a tenon 25 forwardly offsetting from the forward end of a butt-stock 26, which latter is suitably bored out to accommodate the receiver-shank 21 and the screw 23. 70

The upper rear corner of the receiver body 10 is provided with a rearwardly-extending top tang 27 fitting into a notch 28 in the forward upper corner of the butt-stock 26 and having its upper surface contoured to form a symmetrical 75 continuation of the upper surface of the receiver body proper.

Downwardly projecting from the top wall 11 of the receiver body 10 is a lip 29, the outer face of which forms a seat 29^a inset below the 80 adjacent open side edge of the body to a degree sufficient to accommodate the upper edge of a closure plate 30 so as to support the upper end thereof. The rear end of the closure plate rests upon a seat 31 formed in the outer face of the 85 rear wall 13 and inset therefrom to approximately the same degree as is the outer face of the lip 29. Similarly, the outer face of the bottom wall 12 is inset below the general plane of the open side face of the receiver body to provide 90 a seat 32 for the support of the rear portion of the lower edge of the closure plate 30.

The forward portion of the upper edge of the closure plate 30 is notched as at 33 to provide an ejection-opening 34 leading outward from 95 the forward end of the cavity 16 within the said body 10, the forward end of the top wall 11 of which latter being cut away as at 35 to complement the said notch 33 in the closure plate 30 in providing ample clearance for the ejection 100 of empty shells. The forward end of the closure plate 30 is formed upon its inner face with a vertical cut 36 resulting in the formation of a forwardly-extending tongue 37, the inner face of which is adapted to rest against a seat 38 105 formed in the outer face of the forward wall 14 of the body 10 slightly below the facial plane thereof.

The seats 29^a, 31, 32 and 38 are preferably 110 depressed below the general plane of the open

side face of the receiver body 10 to permit the closure plate 30, when installed in place, to symmetrically complement the contour of the said body.

5 The forward portion of the bottom wall 12 of the receiver body 10 is cut away to provide a loading-opening 39 affording access into the hollow interior of the said body between the side wall 15 thereof and the closure plate 30, as clearly shown in Fig. 3, and from which access may be had to the magazine-tube 18. Preferably, the lower inner corner of that portion of the side wall 15 of the body 10 lying in line with the loading-opening 39 is beveled as at 40, as is also the similar edge 41 of the closure plate 30.

About midway its length, the closure plate 30 is formed upon its upper edge with an upwardly-extending interlocking tongue or retaining projection 42 of curved form from front to rear and adapted to fit into a similarly-shaped socket 43 formed in the top wall 11 of the body 10 outwardly adjacent the lip 29 depending therefrom. The front wall of the socket 43 just referred to serves as an inwardly-facing retaining-shoulder 43a.

Supplementing the interlocking tongue 42 of the closure plate, we employ a pair of complementary screws 44 and 45, the former of which extends through a countersunk passage 46 adjacent the lower rear corner of the closure plate 30 and into a threaded bore 47 formed in the body 10 adjacent the junction point of the seats 31 and 32 thereof, while the latter screw 45 extends through a countersunk passage 48 formed in the closure plate 30 adjacent the forward upper corner thereof and into a threaded bore 49 extending inwardly from the seat 38 in the receiver body 10.

40 Depending from the bottom wall 12 of the receiver body 10 is a trigger-guard 50 formed integral therewith and capable of being rough-formed in a forging operation simultaneously with the forging of the cavity 16 in the said body-member 10.

45 By forging or otherwise forming a receiver body with an open side face, the same may be produced at a relatively low cost inasmuch as a large number of cutting operations need not be performed in order to hollow out the interior of the receiver, in accordance with more general practice. Furthermore, when the receiver is formed in two parts, including a body having an open side face and a closure plate for normally closing the same, it is possible to expeditiously perform machining operations within the receiver, as well as to install, inspect and adjust moving parts, etc., therein.

50 By the particular construction shown, in which the receiver is formed with integral top, bottom, front and rear walls, a strong and sturdy receiver may be provided, notwithstanding the fact that the same is made in two parts. By simply stopping the bottom wall 12 short of the forward end of the body-member, a convenient

loading-opening is provided which extends, as may be observed by reference to Fig. 3, between the side wall 15 and the closure plate 30. Furthermore, an ejection-opening complementing the loading-opening 39 just above referred to is readily formed by notching the forward upper edge of the closure plate 30.

55 By providing an interengaging tongue and a socket, one of which forms a feature of the body-member and the other of which forms a feature of the closure plate, we are enabled by the addition of but simple and unobtrusive fastening-means, such as the screws 44 and 45, to secure the closure plate 30 solidly in place in such manner that the receiver appears at a casual glance to be of one-piece construction.

60 It will be understood by those skilled in the art that our invention may assume varied physical forms without departing from our inventive concept, and we, therefore, do not limit ourselves to the specific embodiment herein chosen for illustration, but only as indicated in the appended claims.

We claim:

1. In a firearm receiver the combination with a hollow unitary receiver body having an open side face to permit lateral access thereto and having top and bottom walls; of a pair of complementary seats respectively formed adjacent the front and rear ends of the said receiver body 10; in a plane below the adjacent surface thereof; a closure plate covering the open side face of the said receiver body and seated upon the said complementary seats therein; a retaining-shoulder and a complementary retaining-projection, one of which forms a feature of the top wall of the said receiver body intermediate the front and rear ends thereof and the other of which forms a feature of the top edge of the said closure plate intermediate the front and rear ends thereof, and both of which are adapted for interengagement to assist in the retention of the said plate; and fastening means extending into the said complementary seats respectively formed at the front and rear ends of the said receiver body for holding the said closure plate in place thereon.

2. In a firearm receiver the combination with a hollow unitary receiver body having an open side face to permit lateral access thereto and formed with a pair of complementary seats respectively located adjacent its front and rear ends and formed in its top wall at a point intermediate the said seats with a retaining-notch; of a closure plate covering the open side face of the said receiver body in position to engage the complementary seats therein and provided in its upper edge with an offsetting retaining-projection adapted to engage with the said retaining-notch of the receiver body; and fastening means extending into the said complementary seats at the front and rear ends of the said receiver body for holding the said closure plate in place therein.

FRANK F. BURTON.

WILLIAM C. ROEMER.
